DISPLAY RAIL

Glenn E. Hill, Los Angeles, Calif., assignor to
Irvin A. Brock, Los Angeles, Calif.

Application June 15, 1948, Serial No. 33,140

6 Claims. (Cl. 5—287)

1

This invention relates generally to a bed display rail and more particularly to a shortened side rail connector for supporting the head and foot boards of a bed in proximity for display purposes.

It is a primary object of the invention to provide a bed display rail which will hold the head and foot boards of a bed in proximity and rigidly connected to prevent either horizontal or vertical dislocation or separation.

It is a second object of the invention to provide a bed display rail which may be adjusted so as to be applicable to all normal wooden bed structures.

Another object of the invention is to provide a bed display rail which is simple and inexpensive, but will effectively hold the head and foot boards for display purposes.

It is yet another object of the invention to provide a bed display rail which may be easily applied to the head and foot boards and may be easily adjusted to compensate for any variance in the dimensions of these boards.

These and other important objects will be made apparent from a study of the following specification and the accompanying drawings. The invention, in a preferred form, is illustrated fully in the drawings and hereinafter more fully described.

In the drawing:

Figure 1 is an elevation of the bed display rail in operative position connecting two bed posts.

Figure 2 is a similar elevation showing the bed display rail in inoperative position, in which position it may be applied to the bed posts and thence adjusted to the position shown in Figure 1.

Figure 3 is a bottom view of the display rail showing further details of construction.

As shown in the drawings:

The reference numeral 5 indicates generally a spacer plate, preferably constructed of metal, having rectangular upturned flanges 7 and 9 at either end thereof. Centrally mounted by rivets or welding near the top of the plate 5 is a smaller plate 11 which has a rectangular upturned flange 13. This flange 13 has a central opening 15 for reception of a threaded bolt or screw 17, vertically disposed with a thumb nut 19 fastened permanently to its upper extremity immediately above the flange 13. A cylindrical washer 21 is fixed on and surrounds the bolt 17 and is disposed between the thumb nut 19 and the flange 13. Hexagonal nut 23 is on the bolt 17 in rigid engagement therewith, but below the flange 13, permitting the bolt 17 to rotate in the flanged

2

support 13. The washer is optional and may be omitted as in Fig. 2.

Two other nuts 25 and 27 are mounted rotatably on the bolt or screw 17 and are held in spaced relationship by a pivot member 29 which comprises two plates which loosely encompass the bolt 17 and are pinned together as at 31 and 33. Arms or levers 35 and 37 are pivotally supported on these pins 31 and 33 and extend through slotted apertures 39 and 41 in the rectangular flanges 7 and 9 respectively terminating in hooks 43 and 45 which are adapted to engage the cross pins in the head and foot posts of a bed.

When the display rail is in the position shown in Figure 2 it will be understood that the head and foot posts of a bed 47 and 49 may be brought against the flanges 7 and 9 with the hooks 43 and 45 of the arms or levers 35 and 37 disposed immediately above the cross pins 51 and 53 of the bed posts. Rotation of the thumb nut 19 and bolt 17 will cause vertical motion of the nuts 25 and 27 and the pivot member 29 whereby the arms or levers 35 and 37 will be pivoted into the position shown in Figure 1 with the hooks 43 and 45 engaging the cross pins 51 and 53 to hold the bed posts firmly against the flanges 7 and 9 of the spacing plate 5. It should be further noted that the pivotal action causes the hooks 43 and 45 to so move around the cross pins 51 and 53 as to prevent the separation of the posts from the rail even when vertical stress is applied to the posts. The bed posts can, of course, be detached from the rail by turning the thumb nut 19 in the opposite direction until the position of the toggle levers 35 and 37 is again that shown in Figure 2.

I am aware that many changes may be made and numerous details of construction varied throughout a wide range without departing from the principles of this invention, and I therefore do not propose limiting the patent granted hereon to this specific disclosure, but give reference instead to the appended claims.

I claim as my invention:

1. In a bed display rail, a spacing member, arms pivotally and slidably mounted on said member, hooks on the extremities of said arms adapted to engage cross pins in the head and foot posts of a bed, and a thumb screw on the member and connections between the thumb screw and the arms for moving said arms to draw the head and foot posts of the bed against the spacing member.

2. In a bed display rail, a spacing plate with flanged ends, apertures in said flanged ends,

arms mounted on said plate with their ends extending through said apertures, means for engaging the head and foot sections of a bed on the extremities of said arms, a screw mounted on a support on the plate means pivoted to said arms and engaging said screw for moving said arms to draw the head and foot sections of the bed against the flanged ends of the spacing plate.

3. In a bed display rail a spacing member, hooked arms pivotally and slidably mounted on the spacer member adapted to engage the head and foot posts of a bed, a pivot member connecting said arms, screw means mounted on said spacing member and connected to said pivot member whereby said bed posts may be drawn by the 15 hooked arms against the spacing member.

4. In a bed display rail, a flanged plate, two arms with hooked extremities pivotally and slidably mounted on the plate adapted to engage cross pins in the head and foot posts of a bed, a pivot member connecting said arms, manually actuatable screw means mounted on said plate and movably connected to said pivot member.

5. In a bed display rail, a spacing plate with flanged ends, apertures in said flanged ends, a 25

screw mounted rotatably on said plate, a pivot member mounted on said screw for axial movement with respect thereto, and levers pivotally mounted on said pivot member and extending through the apertures in said flanged ends.

6. In a bed display rail, a spacing plate with flanged ends, apertures in said flanged ends, a screw mounted rotatably on said plate, a pivot member mounted on said screw for axial movement with respect thereto, levers pivotally mounted on said pivot member and extending through the apertures in said flanged ends, and hooks on the extremities of the levers.

GLENN E. HILL.
